HAIR CURLING DEVICE

John R. Joganic, Pittsburgh, Pa.

Application February 10, 1936, Serial No. 63,198

2 Claims. (Cl. 132—36.1)

This invention relates to new and useful improvements in hair curling clamps more particularly known as clamps for Croquignole waving of the hair.

5 So-called permanent waving embodies the steps of subjecting selected strands of hair to a moisture application and then rolling the strands from their free extended ends on a curling spool, the hair being wound taut on said spool, which is 10 then mounted on supporting brackets of the head clamp, which is also adapted to receive a heating element that envelopes the curled hair, and by means of which a heat application to the hair produces a so-called permanent curling or waving thereof.

15 It is well-known to those skilled in the use of Croquignole waving apparatus that in the final period of heat application, the scalp of the head portion adjacent the clamp is subjected to an intense and very frequently injurious heat, causing burns and scalp wounds that subject the operators to vexatious litigation for damages.

20 It is among the objects of the present invention to overcome these difficulties by providing a cooling medium to the strands of hair adjacent the scalp and to apply the cooling medium in a direct and positive manner.

25 A further object of the invention is the provision of simple and expedient means for so applying a cooling medium.

30 Still a further object of the invention is to so direct and distribute the cooling medium to the hair and/or scalp as to not interfere with the necessary heat application to the hair to be 35 treated, while preventing the application of heat through conduction or radiation to the scalp parts adjacent the hair strands.

35 The invention will become more apparent from a consideration of the accompanying drawing 40 constituting a part hereof in which like reference characters designate like parts and in which:

45 Fig. 1 is a plan view of a clamp which in appearance is generally of the type commonly used in the permanent waving of hair;

50 Fig. 2 a view in perspective of the clamp shown in Fig. 1 on the side opposite to that shown in Fig. 1 and illustrates one embodiment of this invention;

55 Fig. 3 is a similar view of the clamp closed, which is the position in which the hair is engaged; and

Fig. 4 is a view in perspective of a tube constituting the seat or foot of the clamp which is the portion placed adjacent the scalp or scalp 55 protector provided for such purposes.

The elements of the clamp shown in the several figures of the drawing which are common to such clamps in conventional use are the hinge members 1 and 2, hinged at 3, constructed of superposed plates for clamping rubber strips 4 and 5 between which strands of hair are engaged. The hinge members 1 and 2, when closed, are provided with upstanding bracket elements 6 and 7 for engaging the journals or extensions of a curler or roll on which the hair is wound, 10 these rollers snapping in place when mounted in the supporting brackets of the clamps. The clamp is closed when the hinge members are juxtaposed, as shown in Fig. 3, by means of a clamping lever 8, which has a cam-like surface 15 9 that engages a groove or notch 10 in the member 2.

The new features of the clamp are shown in Figs. 2 to 4 and consist of a pair of elongated blocks or hollow tubes 11 which are closed at the ends 12 and communicate at one end with a bifurcated tube 13, preferably of flexible material such as rubber, which connects through a manifold, not shown, with a source of cooling medium such as air, from a blower or fan. The elements 11 are preferably made of fiber or other non-metallic substance to render them non-corroding, such material being preferably of a low heat conducting quality. A series of perforations 14 extend on the inner wall of the members 11 to 30 impinge the cooling fluid against the hair strands engaged between the rubber clamping faces 4 and 5.

As previously explained, Figs. 2 and 3 are bottom views of the clamp, and the fiber tube elements 11 are adjacent or nearest the scalp. It is common practice to employ a pad of insulating material directly adjacent the scalp so that the members 11 are placed against the insulating pads and in effect constitute feet for the clamp 40 elements.

In use, the cooling medium, such as air, need not be applied immediately upon the application of heat to the curled hair. Heat is applied in a well-known manner, by electrical resistor heating elements or so-called steam boxes or covers, which are shaped to envelope or engage the hair on the curling spool, not shown, and which constitutes no part of the present invention.

However done, the final stages of the application of the heat, which is the period during which the moist hair is intensely heated and by conduction transmits the heat to the scalp, the cooling fluid is turned on. The cooling fluid flows through the flexible conduit 13 into the hollow 55

members 11, thence it is impinged through perforations 14 against the hair strands extending along the face of the clamping members 4 and 5 to cool them.

5 Thus at the critical time, the scalp is maintained in a cool and comfortable condition, and scalp injury by burning or injury to the hair by excessive heating is entirely avoided.

Although one embodiment of the invention has 10 been herein illustrated and described, it will be obvious to those skilled in the art that various modifications may be made in the details of construction without departing from the principles herein set forth.

15 I claim:

1. A device for permanent waving of hair, comprising a pair of hinged members constituting a clamp for engaging the hair strands adjacent the scalp preliminary to the curling of the strands 20 and adapted to receive a curling rod, means for locking said members in closed position, a foot for each of said hinged members joined thereto in the base of the clamp, said foot elements being of hollow construction having perforations on 25 the same side and coextensive with the hair engaging faces of the clamp, and said foot ele-

ments being closed at one end and having connections with a source of cooling medium at their other end to direct the cooling medium through the perforations against the hair adjacent the scalp.

2. A device for permanent waving of hair, comprising a pair of hinged members constituting a clamp for engaging the hair strands adjacent the scalp preliminary to the curling of the strands and adapted to receive a curling rod, means for locking said members in closed position, a foot for each of said hinged members comprising a rectangular shaped member of fibrous material having a hollow interior closed at one end and open at the other, said members being spaced 10 from the clamping faces of the hinged member to be out of alignment therewith and having perforations on the same side and coextensive with the hair engaging faces of the clamp, and a bifurcated tube having a leg inserted in the open 15 ends of each of said perforated members and having a connection for a source of cooling medium which is adapted to be impinged upon the hair adjacent the scalp through the perforations of the rectangular members.

25 JOHN R. JOGANIC.
